(57) **CLAIM**

The ornamental design for a fastener driving tool housing, as shown and described.

DESCRIPTION

FIG. 1 is a right side elevational view of the fastener driving tool housing showing my new design;

FIG. 2 is a left side elevational view thereof;

FIG. 3 is a front elevational view thereof;

FIG. 4 is a rear elevational view thereof;

FIG. 5 is a top plan view thereof; and,

FIG. 6 is a bottom plan view thereof.

The broken lines showing portions of the fastener driving tool are for illustrative purposes only and form no part of the claimed design. In those locations where depiction of the broken line structure would be in front of the claimed portion of the design and limit understanding of the fastener driving tool housing, the broken lines have not been depicted.

The symbol displayed on the top of the fastener driving tool housing is a trademark owned by Illinois Tool Works Inc. of Glenview, Ill. 60026.
